UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEWING-MACHINE.

1,205,333.

Specification of Letters Patent. Patented Nov. 21, 1916.

Application filed January 14, 1913. Serial No. 741,929.

To all whom it may concern:

Be it known that I, ALBERT H. DE VOE, a citizen of the United States, residing at Westfield, in the county of Union and State 5 of New Jersey, have invented certain new and useful Improvements in Sewing-Machines, of which the following is a specification, reference being had therein to the accompanying drawings.

10 This invention has for its object to provide a sewing-machine adapted for uniting and serging in a single operation the edges of fabrics, and particularly the overlapping margins of the soles and uppers of that class 15 of Japanese footwear known as "tabis."

It has for further objects to provide means for varying the spacing of the loops of binding thread for the raw edges of fabric without changing the length of the 20 stitches, to so apply either a single binding thread or two crossed binding threads, and to provide means whereby a machine so fitted may be converted into a straight-away stitching machine capable of operation with- 25 in the body portion of a fabric intermediate the margins.

The present improvement is preferably embodied in a sewing machine having straight-away stitch-forming and feeding 30 mechanisms of any usual or suitable type. Disposed upon the opposite side of the work-support from the reciprocating needle are two rocking supports journaled to oscillate and slide upon fixed fulcrum-pins parallel 35 with the needle. Each of these rocking supports sustains a preferably eye-pointed thread-carrying implement adapted to present to the needle alternately above and below the work-support a binding-thread loop 40 adapted to be entered by the needle in its succeeding thrust.

The rocking supports derive their simultaneous oscillatory movements from an operative connection with a countershaft 45 mounted independently of the main-shaft and having independent connections with said supports from which the latter receive reciprocal rising-and-falling movements lengthwise of their respective fulcrum-studs. 50 The actuating countershaft for the thread-carrying implements preferably has an operative connection with the main-shaft which actuates the primary stitch-forming mechanism, including the needle and coop-

erating loop-taker, whereby it may be driven 55 at different speeds relatively to the main-shaft or wholly disengaged therefrom, a clutch being in the present instance employed to change or wholly disengage the connection between the countershaft and 60 main-shaft.

Figure 1 is a front side elevation of a sewing machine embodying the present improvement, with the frame in section, and Fig. 2 a bottom plan of the same. Fig. 3 65 is a rear side elevation of the machine and Fig. 4 a plan thereof with portions of the arm and bed-plate removed to expose certain parts beneath the same. Fig. 5 is a front end view of the lower portion of the 70 machine with the bed-plate in section, Fig. 6 is a perspective view of the throat-plate and operative portion of the presser-foot, Fig. 7 is a perspective view of the thread-carrying implements and actuating means 75 therefor, and Fig. 8 a similar view of the binding thread pull-off device. Figs. 9 and 10 are sectional views, taken from different sides, of a portion of the countershaft with its change-wheels and clutch device, and 80 Fig. 11 a transverse section of the same. Figs. 12 and 13 are perspective views, upon a larger scale, of two of the elements of the clutch device. Figs. 14 and 15 are perspective views showing the relative positions of 85 the binding-thread carrying implements in different stages of the seam-forming operation. Fig. 16 is a perspective view showing diagrammatically one form of seam which the present machine is fitted to produce. 90

As represented in the drawings, the machine frame comprises the usual bed-plate 1 from which rises the bracket-arm standard 2 with tubular overhanging member 3 terminating in the hollow head 4 in which is 95 journaled the reciprocating needle-bar 5 carrying the eye-pointed needle 6. The needle-bar has fixed thereon the collar 7 provided with the usual stud 8 embraced by the boss at one end of the pitman 9 whose 100 other end is connected with a crank-pin upon the crank-arm 10 fixed upon the forward end of the main-shaft 11 which is journaled in the member 3 of the bracket-arm and has fixed upon its rearward end 105 the belt-pulley 12. The main-shaft has formed therein the actuating crank 13 connected by the pitman 14 with the rocker 15

operatively connected with the loop-taker actuating rock-shaft 16 carrying at its forward end the driver 17 for the shuttle 18 journaled in the race 19 for coöperation 5 with the needle 6 and provided with the thread-case 20, as is common to a certain type of Singer machine.

The main-shaft carries the usual cam or eccentric 21 connected by means of the link-bar 22 with the feed-actuating rock-shaft 23 provided with the usual yoke 24 to which is pivotally connected one end of the feed-bar 25 carrying the feed-dog 26. The forked opposite end of the feed-bar embraces the 15 lateral stud 27 of a crank-arm 28 upon the feed-lift rock-shaft 29 connected by means of the pitman 30 with the feed-lift eccentric 31 upon the main-shaft.

Secured to the lower end of the presser-bar 32 is the shank 33 of the presser-foot formed with the foot-plate 34 having the spaced ears 35 by means of which it is pivotally connected by the pin 36 to the lower end of the shank 33. The foot-plate 34 operates 20 in the usual manner with the feed-dog 26 passing through the apertures 37 of the throat-plate 38 which has the usual needle-aperture 39 communicating with one of the feed-dog apertures 37 by the slot 40 and also with the laterally extending aperture 41 through which the binding-thread carrying implements pass in their coöperation with the needle alternately above and below the throat-plate.

Secured upon the bottom of the bed-plate 1 by fastening screws 42 is the foot 43 of a hanger 44 formed with a lateral arm or member 45 having sockets in which are secured by set-screws 46 the lower ends of the 40 laterally spaced stud-pins 47 and 48 disposed substantially parallel with the needle-bar 5 and having their reduced and threaded upper ends 47' and 48' tapped into the bearing plate 49 secured upon the bed plate 1. Journaled upon each of the stud-pins 47 and 48 are the rocking and sliding sleeves 50 and 51 provided at their upper ends with the lateral arms 52 and 53 each formed with a substantially radial socket in which is secured 50 by means of the set-screws 54 the shank 55 of one of the thread-carriers 56 and 57 provided with a thread channel extending lengthwise thereof and terminating in the aperture 58.

Secured upon the lower portion of each 55 of the sleeves 50 and 51 by means of a clamp-screw 59 is a split collar 60 formed with a laterally and downwardly extending arm 61 which is provided with an aperture parallel with the fulcrum-stud pins 47 and 48. Loosely journaled upon the lower portion of the stud-pin 48 is the boss 62 of a rock-lever formed with the angularly disposed arms 63 and 64. The rock-lever arm 65 carries near the extremity of its upper

face the roller-stud 65 and intermediate the same and the boss 62 the laterally disposed boss or projection 66 in which is rigidly secured the upwardly extending pin 67 slidably fitted within the aperture of the arm 61 of the sleeve 51. The rock-lever arm 64 is pivotally connected by means of the screw-pin 68 with one end of a link 69 whose opposite end is similarly connected by means of the screw-pin 70 with an arm 71 of a 75 rock-lever having a boss 72 journaled upon the lower portion of the stud-pin 47 and a second arm 73 provided in its outer end with the upwardly extending pin 74 slidably fitted within the apertured arm 61 of 80 the sleeve 50. By the means just described, the oscillatory movement of the rock-lever 63 64 imparts simultaneous endwise reciprocal movements in substantially the same direction to the thread-carriers 56 and 57 while permitting them to perform independently their requisite rising and falling movements.

Journaled upon the rocking sleeves 50 and 51 intermediate their respective arms 52 and 53 and the split collars 60 are the loose sleeves 75 and 76 each provided with a lateral lug 75' and 76' having a transverse bearing aperture. These bearing apertures are entered by stud-pins 77 and 78 projecting from the forward faces of the links 79 and 80 having at the opposite ends of their rearward faces similar stud-pins 81 and 82, the stud-pins 77 and 78 being confined within their respective bearing apertures by 100 means of the screws 83 tapped into their extremities, as shown in Fig. 7. The stud-pins 81 and 82 enter respectively bearing apertures of the bosses 84 and 85 sustained by the oppositely extending crank-arms 86 of 105 a collar 87 secured by means of the set-screw 88 upon the forward end of the rock-shaft 89 which is journaled in the hanger 44 parallel with the loop-taker shaft 16.

The rock-shaft 89 has secured to its opposite end by means of the set-screw 90 the hub of a lateral crank-arm 91 which carries the ball stud-pin 92 embraced by a strap at the lower end of the pitman-rod 93 provided at its opposite end with a similar 115 strap embracing the ball stud-pin 94 carried by the lateral arm 95 of a bellcrank mounted upon the fulcrum screw-stud 96 and having the upwardly extending arm 97 terminating in the split socket 98. The 120 socket 98 has a bushing 99 in which is mounted the pin 100' projecting from the shoe 100 affording a follower for the double switch-cam 101, of well known construction, mounted upon the countershaft 102 journaled in the bearing bosses 103 of the bracket-arm 3.

At its forward extremity, the countershaft 102 carries an eccentric stud-screw 104 constituting a crank-pin which is embraced 130

by the perforated boss 105 near the upper end of the pitman-rod 106 having at its lower end the apertured boss 107 embracing the stud-screw 108 carried by the crank-arm 109 whose hub 110 is secured by means of the set-screw 111 upon the rearward end of the rock-shaft 112 journaled in suitable bearing members of the hanger 44. Fixed upon the forward end of the rock-shaft 112 is the cam-cylinder 113 formed with the cam-groove 114 entered by the roller-stud 65 of the rock-lever arm 63. By its connection with the rock-shaft 89 through the pitman 93, bellcrank 95 97 and switch-cam 101, the countershaft 102 imparts rocking movements from which are derived through the links 79 and 80 and sleeves 75 and 76 the rising and falling movements of the thread-carriers 56 and 57; while said countershaft 20 imparts to the rock-shaft 112 through the crank-pin 104, pitman 106 and crank-arm 109 rocking movements from which are derived through the cam 113, rock-lever 63 64 and the other described connections the reciprocal endwise movements of the thread-carriers.

Secured upon the top of the bracket-arm 3 between the guide-ribs 115 by means of the screw 116 are the shanks of the laterally extending nipper-arm 117 and the yielding guide-arm 118 beneath it. The guide-arm 118 is forked in its outer end to form a member 119 having at its inner edge an upturned lip 120 with suitable thread-guiding apertures and a second member 121 having upon opposite edges the upturned lips 122 and 123 of which the former has thread-guiding eyes in alignment with those of the lip 120 and the latter is formed with open slots 124 for a like purpose.

The upper extension 106' of the pitman-rod 106 is formed at its extremity with a pull-off cam finger 125 which has a circular path of movement between the members 119 and 121 of the guide-arm 118, and in its upward and backward movement engages the binding threads *c* and *d* for drawing off the same from the source of supply, as represented in Fig. 8. The arm 118 is preferably made of spring steel, and its member 121 is normally spaced slightly below the lower face of the arm 117 to permit the binding threads to normally pass freely between the same. The pitman-rod extension 106' carries adjacent the pull-off finger 125 the lateral roller-stud 126 which, as the pitman-rod rises, presses the member 121 upwardly to nip the thread between the latter and the arm 117, whereby the pull-off finger 125 is caused to act wholly between the nipper thus formed and the binding thread supply.

The rearward portion of the countershaft 102 is made tubular to provide an axial recess or socket 127 which is intersected at the rearward extremity by a transverse slot 128.

Surrounding the slotted portion of the shaft 102 and confined between the rearward bearing 103 and a disk 129 secured thereto by screws 130 are the hubs 131 and 133 of two gear-wheels 132 and 134 loosely mounted for independent rotation thereon and each provided in one side with a groove or keyway 135 and 136, respectively. Disposed within the transverse slot 128, and confined between the forward end of the same and the disk 129, is a coupling plate 137 having upon the opposite edges and at opposite ends the lateral extensions or feathers 138 and 139 and an intermediate recess or opening 140 extending from the forward end.

Embraced by the opposite walls of the recess or opening 140 is the rounded extremity 141 of a shift-lever 142 having intermediate its ends the perforated boss 143 journaled upon the transverse pin 144 passing through the countershaft 102 and having its opposite end portion reduced to a thin wire 145 sufficiently resilient to yield at certain times in shifting the lateral position of the coupling plate 137. The member 145 of the shift-lever passes loosely through a central aperture 146 and through the transverse slots 147 formed in the opposite faces of the endwise movable shift-pin 148 journaled in and transversely of the countershaft 102 and 95 at right angles to the fulcrum-pin 144.

Secured upon the shaft 102 by means of set-screws 149 is a collar 150 apertured to receive the opposite ends of the pin 148 and formed with recesses 151 surrounding the 100 same to provide access to the ends of the pin. The shift-pin 148 is provided centrally with three nicks or notches 152 adapted to be entered by the conical point of a yielding detent-pin 153 journaled within a socket in 105 the shank of the screw 154 tapped into the side of the shaft 102 and pressed normally inward by means of a spring 155. The pressure of the spring may obviously be adjusted by turning the screw 154 in one or the 110 other direction to vary the action of the detent-pin 153 upon the shift-pin 148.

Fixed upon the main-shaft 11 intermediate the hub of the pulley 12 and the bearing bushing 2' are two driving gears 156 and 157 115 meshing respectively with the loose gears 132 and 134 upon the countershaft 102, the gear 157 being of one-half the diameter of the gear 134 meshing therewith and the intermeshing gears 156 and 132 being of the 120 same size, thereby providing for the turning of the countershaft at the same speed or one-half the speed of the main- or driving shaft, depending upon which of the loose gears is coupled to the countershaft by the coupling 125 plate 137.

The presser-foot and throat-plate are provided with the usual superposed stitch-sustaining or chaining fingers 34' and 38' (Fig. 6). Secured to the bed-plate by screws pass- 130

ing through apertures 158 is the foot 159 of a work-guide whose shank portion 160 has at its forward extremity the upturned lip 161 to which is secured by screws 162 the 5 edge-guiding plate 163 arranged in the direction of feed and terminating at its rearward end in a slightly tapered guiding and stitch-supporting finger 164 extending to a point substantially opposite the extremity of 10 the throat-plate finger 38'.

In preparing the machine for sewing, the needle-thread *a* is led from the source of supply through the usual tension device and take-up and thence through the eye of the 15 needle 6, and the lower thread *b* is led from the bobbin-case 20 upwardly through the needle aperture of the throat-plate. The binding threads *c* and *d* are led from the source of supply through their respective 20 apertures of the guide-plate 118 and tension devices 165 and 166 upon the front side of the bracket-arm, and thence downwardly through the eyes of the respective thread-carrying implements 56 and 57. 25 When the shift-lever 142 of the coupling device is in central position, as represented in Figs. 9, 10 and 11, both the gears 132 and 134 are disconnected from driving relation with their supporting shaft 102, and rotate 30 idly thereon at different speeds under the action of the driving gears 156 and 157. As so adjusted, the machine is in condition for plain stitching, the thread-carriers 56 and 57 being arranged substantially in the 35 dotted-line position of Fig. 15 nearly flush with the top of the throat-plate, so that, the edge guide 160 163 being removed, the machine is adapted for performing straight-away stitching in any part of a fabric presented to the stitch-forming and feeding mechanisms without obstruction by either of the thread-carriers.

By pressure upon one end of the shift-pin 148, the latter is moved into an extreme position wherein it is detained by the detent-pin 153 and the resilient portion 145 of the shift-lever 142 is bent laterally and presses the coupling plate 137 in the opposite direction until the keyway 135 of the gear 132 45 comes into register with the feather 138, when the latter snaps into it and couples the gear 132 to the countershaft whereby the latter is caused to rotate in unison with the main-shaft. In this relation of the parts, 50 the thread-carriers 56 and 57 receive from the actuating crank-pin 104 through the connections including the pitman-rod 106 and the rock-shaft 112 and cam 113 simultaneous endwise movements transversely to the direction of feed and across the edge-guide 163; while they derive from the switch-cam 101 reciprocal rising and falling movements of one-half the frequency of their endwise movements.

65 As the machine is thus adjusted, the mar-

ginal portion of two or more plies of fabric *m* to be united and serged is introduced between the pressure-foot and throat-plate and in contact with the edge-guide 163, and the machine set in motion. As the needle descends, it passes successively between the blade of the thread-carrier 56 and its thread *c* leading around the finger 164, through the throat-plate and between the thread carrier blade 57 and its respective binding thread *d* 70 leading upwardly and around the finger 164, as represented in Fig. 14. As soon as the binding threads have been caught by the needle, the carriers 56 and 57 begin to retreat laterally while the needle completes its descent and begins to rise to present its loop for seizure by the shuttle. During the rise of the needle, the thread-carriers complete their retreat to extreme retracted position, then perform their reciprocal vertical movements and finally advance each to substantially the position formerly occupied by the other in presenting its loop for passage by the needle, the needle-thread loop having meanwhile been cast about the bobbin-case 90 and the stitching threads thus interlocked drawn up into the work in the usual manner. In the succeeding stitch-forming operation the coöperation of the needle with the thread-carriers and the shuttle is precisely the same, excepting that each of the thread-carriers has assumed the operative relation with the needle formerly occupied by the other, (Fig. 15).

It will be seen that the rocking sleeves 50 100 and 51 afford endwise movable supports for the thread-carrying implements, each sleeve moving lengthwise of its axis to position its lateral arm and thread-carrying implement prior to the advance and retraction of the 105 latter.

By the operation above described, a combined straightaway and binding seam is produced such as that represented in Fig. 16, in which loops of needle-thread *a* and shuttle-thread *b* entering opposite faces of the work are embraced alternately by loops of the two binding threads *c* and *d* which cross each other upon the edge of the fabric.

By removing either of the thread-carriers 115 56 and 57 from its respective rocking support, or unthreading the same, a seam will be formed with a single binding thread caught by the stitching thread loops alternately above and below the fabric. Such 120 fabrics which are closely woven and of which the raw edges require to be bound only at intervals to prevent raveling.

By throwing the shift-pin into its opposite extreme position, the gear 132 is uncoupled from and the gear 134 is coupled to the countershaft, whereby the latter is caused to be driven at one-half the speed of the main-shaft. By such adjustment of the machine, 130

a seam similar to that of Fig. 16 is produced, excepting that the binding thread loops are caused to embrace only the alternate stitching-thread loops upon the opposite faces of the fabric; and by removing or unthreading one of the binding thread-carriers a single binding thread may be laid across the edge of the fabric with its loops caught by the stitching threads alternately and at every fourth stitch upon each face of the fabric.

To insure against the breaking or bending of the thread-carriers in their advance or loop presenting positions by the lifting of the presser-foot, the presser-foot is preferably provided with a stop-collar 167 secured adjustably thereon by means of the set screws 168, so that when the presser-bar rises under the action of the finger lifting lever 169 or the knee-actuated lever 170, it is arrested by engagement of the stop-collar 167 with the lower end of the bracket-arm head 4.

While the present improvement is shown herein in what is considered its preferable form, it is to be understood that it is susceptible of considerable modification in the construction, form and arrangement of its component parts without departure from the scope of the present invention.

Having thus set forth the nature of the invention, what I claim herein is:—

1. In a sewing machine, in combination, a reciprocating needle, a coöperating loop-taker, a thread-carrying element having uniform, successive, reciprocatory movements and coöperating with said needle independently of the loop-taker, and means under manually selective control for changing the frequency of action of said implement relatively to the needle movements.

2. In a sewing machine, the combination with a reciprocating needle and a coöperating loop-taker, of a plurality of thread-carrying implements coöperating with said needle at different points in its path of reciprocation, and means for changing the frequency of action of said implements relatively to that of the needle movements.

3. In a sewing machine, the combination with a reciprocating needle and a coöperating loop-taker, of a plurality of reciprocally movable thread-carrying implements coöperating alternately with said needle at the same point in its path of movement, and means for changing the frequency of action of said implements relatively to that of the needle movements.

4. In a sewing machine, the combination with a reciprocating needle and a coöperating loop-taker, of a plurality of thread-carrying implements, an actuating member, operative connections between said actuating member and said implements whereby they are caused to coöperate with said needle at different points in its path of reciprocation,

and means for changing the speed of movement of said actuating member relatively to operative movements of the needle.

5. In a sewing machine, the combination with a reciprocating needle and a coöperating loop-taker, of a thread-carrying implement coöperating with said needle independently of the loop-taker, actuating members for said thread carrying implement, and manually shiftable controlling connections permanently mounted upon the machine for rendering said implement effective or ineffective.

6. In a sewing machine, the combination with a reciprocating needle and a coöperating loop-taker, of a plurality of thread-carrying implements coöperating with said needle at different points in its path of reciprocation, and shiftable controlling connections permanently mounted upon the machine for rendering both of said implements effective or ineffective.

7. In a sewing machine, the combination with a reciprocating needle and a coöperating loop-taker, of a plurality of reciprocally movable thread-carrying implements coöperating alternately with said needle at the same point in its path of movement, and shiftable controlling connections permanently mounted upon the machine for rendering both of said implements effective or ineffective.

8. In a sewing machine, in combination, a work-support, stitch-forming mechanism including a main-shaft, a reciprocating needle and actuating connections between said main-shaft and needle, and means connected with said main-shaft independently of the needle-actuating connections for imparting thereto operative movements about the path of reciprocation of the needle timed to cause said implement to carry a thread to the needle during alternative penetrations thereof and adapted to impart to said implement successive operative movements about the needle-path alternately above and below the work-support.

9. In a sewing machine, the combination with a reciprocating needle and a loop-taker coöperating therewith in each reciprocation thereof at the same point in its path of movement, of a plurality of thread-carrying implements, and means for imparting to said implements operative movements to cause each to present thread-loops to the needle in each alternate reciprocation of the latter and alternately at different points of its path of reciprocation.

10. In a sewing machine, the combination with a work-support, a reciprocating needle, needle-actuating means disposed at one side of the work-support, and a loop-taker coöperating with said needle at the opposite side of said work-support, of a thread-carrying implement, a support therefor ar-

ranged at the same side of the work-support as said loop-taker, actuating means for said implement whereby it is caused to co-operate with said needle alternately at opposite sides of the work-support, and means for rendering said implement-actuating means inoperative.

11. In a sewing machine, the combination with a work-support, a reciprocating needle, needle-actuating means disposed at one side of the work-support, and a loop-taker coöperating with said needle at the opposite side of said work-support, of a plurality of thread-carrying implements, a support for each of said implements arranged at the same side of the work-support as said loop-taker, actuating means for said implements whereby they are caused to coöperate with said needle respectively at opposite sides of the work-support and each to coöperate with the needle alternately at opposite sides of the work-support, and means for rendering said implement-actuating means inoperative.

12. In a sewing machine, the combination with a driving shaft, and a reciprocating needle and complemental loop-taking means deriving operative movements therefrom, of a thread-carrying implement adapted for presenting thread-loops for passage of the needle, actuating means for said implement, change-gearing adapted to afford a driving connection between said shaft and said actuating means whereby the latter may be operated at different speeds relatively to said shaft, and means applied to said change-gearing for controlling the connection of said actuating means with the driving shaft without change in the relative positions of the gearing elements and thereby determining the relative timing of the thread-carrier- and needle-movements.

13. In a sewing machine, the combination with a driving shaft, and a reciprocating needle and complemental loop-taking means deriving operative movements therefrom, of a thread-carrying implement adapted for presenting thread-loops for passage of the needle, actuating means for said implement including a rotary shaft, a plurality of trains of intermeshing gears, each train having one gear fixed upon one of said shafts and another gear loosely mounted upon the other shaft, and means whereby said loosely mounted gears may be coupled to and uncoupled from their supporting shaft.

14. In a sewing machine, the combination with a driving shaft, and a reciprocating needle and complemental loop-taking means deriving operative movements therefrom, of a thread-carrying implement adapted for presenting thread-loops for passage of the needle, actuating means for said implement including a rotary shaft formed with a transverse slot, a plurality of gears of dif-

ferent size each mounted loosely upon said rotary shaft and provided with a keyway, driving gears fixed upon the driving shaft and meshing with said loosely mounted gears, a key-plate fitted within the slot of said rotary shaft and movable successively into and out of engagement with the keyways of said loosely mounted gears, and means for shifting said key-plate to couple and uncouple said loosely mounted gears to and from the rotary shaft.

15. In a sewing machine, the combination with a driving shaft, and a reciprocating needle and complemental loop-taking means deriving operative movements therefrom, of a thread-carrying implement adapted for presenting thread-loops for passage of the needle, actuating means for said implement including a rotary shaft formed with a transverse slot, a plurality of gears of different size each mounted loosely upon said rotary shaft and provided with a keyway, driving gears fixed upon the driving shaft and meshing with said loosely mounted gears, a radially movable key-plate fitted within the slot of said rotary shaft and provided upon opposite edges with projecting portions adapted to enter alternately said keyways of the loosely mounted gears, and yieldingly acting means for shifting said key-plate to couple and uncouple said loosely mounted gears to and from the rotary shaft.

16. In a sewing machine, the combination with a main-shaft a reciprocating needle, complemental loop-taking means and driving connections between said main-shaft and said needle and loop-taking means, of a thread-carrying implement adapted for presenting thread loops for passage to the needle, actuating connections between said main-shaft and implement, a thread nipping plate, and a thread pull-off device including an arm having a thread engaging portion and a portion adapted to operatively engage said nipping plate and deriving its movements from an element of said actuating connections.

17. In a sewing machine, the combination with a reciprocating needle and complemental loop-taking means, of a thread-carrying implement adapted for presenting thread-loops for passage of the needle, actuating means for said implement, a binding thread pull-off device including an operating member deriving its movements from an element of said actuating means, and means for rendering said actuating means inoperative without affecting the needle and loop-takers.

18. In a sewing machine, the combination with a reciprocating needle and complemental loop-taking means, of a thread-carrying implement adapted for presenting thread-loops for passage of the needle, actuating

means for said implement, a binding thread pull-off device including an operating member deriving its movements from an element of said actuating means, and means for varying the frequency of action of said thread-carrying implement relatively to the movements of the needle and loop-taking means.

19. In a sewing machine, the combination with a reciprocating needle and complementary loop-taking means, of a thread-carrying implement adapted for presenting thread-loops for passage of the needle, actuating means for said implement, a binding thread pull-off device including an operating member deriving its movements from an element of said actuating means, and means including a plural-stepped coupling element whereby the action of said actuating means 15 may be arrested or may be varied relatively to that of the needle and loop-taking means.

20. In a sewing machine, the combination with a reciprocating needle and a coöperating loop-taker, of a thread-carrying implement, a rocking support therefor mounted for movement upon an axis substantially parallel with the needle-path, and means for imparting to said support rocking movements upon and bodily reciprocating 25 movements lengthwise of said axis.

21. In a sewing machine, the combination with a reciprocating needle and complementary loop-taking means, of a thread-carrying implement, a rocking support therefor mounted for movement upon an axis substantially parallel with the needle-path, means connected with said support for imparting thereto rocking movements, and means connected to said support independently of its 35 rocking means and adapted to impart to it endwise movements upon its axis of less frequency than said rocking movements.

22. In a sewing machine, the combination with a reciprocating needle and complementary loop-taking means, of a thread-carrying implement adapted for coöperation with said needle, a rocking support therefor mounted for movement upon an axis substantially parallel with the needle-path, two 45 rock-shafts, means for operating them with different frequency, a connection between one of said rock-shafts and said support for imparting rocking movements to the latter, and a connection between the other of said 50 rock-shafts and said support for imparting to it its endwise movements lengthwise of its axis.

23. In a sewing machine, the combination

with a reciprocating needle and complementary loop-taking means, of a thread-carrying 60 implement adapted for coöperation with said needle, a rocking support therefor mounted for movement upon an axis substantially parallel with the needle-path, two rock-shafts, means for operating them with 65 different frequency, an operative connection between one of said rock-shafts and said support and including a sliding and pivotal connection therewith whereby said support is given its rocking movements, a crank-arm 70 upon the other of said rock-shafts, and a link connection between said crank-arm and said support whereby movements are communicated to the latter lengthwise of its axis. 75

24. In a sewing machine, the combination with a reciprocating needle and complementary loop-taking means, of a plurality of thread-carrying implements adapted for independent coöperation with said needle, 80 rocking supports for said implements mounted for movement upon axes substantially parallel with the needle-path, two rock-shafts, means for operating them with different frequency, a cam upon one of said 85 rock-shafts, a plurality of connected rock-levers each having a pivotal and sliding connection with one of said supports, an operative connection between one of said rock-levers and said cam, crank-arms fixed upon 90 the other of said rock-shafts, and link connections between each of said crank-arms and one of said supports for imparting reciprocal endwise movements thereto upon their respective axes. 95

25. In a sewing machine, the combination with a main-shaft a reciprocating needle, and driving connections between said main-shaft and needle; of a thread-carrying implement adapted for presenting thread loops 100 for passage of the needle, actuating connections between said main-shaft and implement, a thread nipping plate, and a thread pull-off arm deriving its movements from an element of said actuating connections 105 and adapted first to operatively engage said nipping plate and secondly to pull off thread.

In testimony whereof, I have signed my name to this specification, in the presence of 110 two subscribing witnesses.

ALBERT H. DE VOE.
